UNITED STATES PATENT OFFICE.

IVAN R. TOMES, OF MASON CITY, IOWA.

SUSPENSION CLAMP.

Application filed April 21, 1923. Serial No. 633,725.

To all whom it may concern:

Be it known that I, IVAN R. TOMES, a citizen of the United States, residing at Mason City, in the county of Cerro Gordo and State of Iowa, have invented certain new and useful Improvements in Suspension Clamps, of which the following is a specification.

This invention relates to suspension devices and has for its object the provision of a novel device constructed and adapted to be clampingly engaged upon the lintel of a door frame for the purpose of suspending a "baby jumper" or the like, the device being particularly advantageous in this capacity inasmuch as it makes provision for the care of an infant or small child, while the mother or other attendant is engaged or busy.

An important and more specific object is the provision of a suspension device of this character which may be used on lintels of different sizes as the parts are so arranged that adjustment is easily and quickly effected to meet different conditions which may exist.

Another object is the provision of a device of this character which may be almost instantaneously removed when such is desired with the expenditure of extremely little effort while at the same time its holding qualities while in use will be certain.

An additional object is the provision of a suspension clamp which will be simple and inexpensive in manufacture, highly efficient in use, durable in service, and a general improvement in the art.

With the above and other objects and advantages in view, the invention consists in the details of construction to be hereinafter more fully described and claimed and illustrated in the accompanying drawings in which—

Figure 1 is a front elevation of the device

Figure 2 is an elevation at right angles to Figure 1.

Figure 3 is a detail cross section on the line 3—3 of Figure 2.

Referring more particularly to the drawings, I have shown the device as comprising a U-shaped frame including a side member 10 formed at its lower end with a knuckle 11 with which are pivotally connected at 12 knuckles 13 formed on an L-shaped member 14 which constitutes the other side of the frame. The upper ends of the members 10 and 14 are formed with lateral extensions 15 directed toward each other and carrying

plates 16 adapted to engage against the wall above the lintel of a door frame. The purpose of the extensions 15 is to permit the side members 10 and 14 to clear the door frame while clamping action by the plates 16 is effected. The suspension means consists of a depending stem or rod 17 suitably secured to the bottom or horizontal portion of the member 14 in any desired manner, as for instance, by passing therethrough, and having its upper end upset, as indicated at 18. The lower end of the stem is formed with a hole 19 within which is engaged a supporting ring 20 within which may be inserted a suspension hook or the like provided on "baby jumpers," swinging cradles, and the like.

For maintaining the members 10 and 14 in clamping engagement, I provide a threaded rod 21 which extends across the U-shaped frame and which has one end pivoted at 22 between spaced ears 23 formed or secured upon the inside of the member 10. The other end of this rod passes through a slot 24 formed in the member 14 and extending inwardly from one edge thereof and this end of the rod carries a wing or other clamping nut 25. The threaded rod is prevented from disengagement from the slot by means of a catch or pawl 26 slidably engaged upon the rod and having a hook-like end 27 which engages against the edge of the member 14 opposite that which is formed with the slot 24.

In applying the device, the nut 25 is loosened and the member 26 moved into its disengaged position so that the rod 21 may be swung out of the slot 24. This leaves the two members 10 and 14 free to swing upon the pivot 12 and the members are then embracingly engaged upon the lintel. Subsequently, the rod 21 is swung into the slot 24, the member 26 is slid along its hooked end 27, engages the edge of the frame member 14, and the nut 25 is screwed down to tighten the clamp. Whether one or two of the devices should be used depends entirely upon the nature of the article to be suspended. In the case of a "baby jumper" or some "walkers" of different varieties, one of the devices may be sufficient though if it is desired to support an infant's hammock or some types of swings, two of the clamps would be necessary as two suspension points are required. Regardless of this point, it

is quite obvious that the device is easy to apply and will efficiently perform its function.

While I have shown and described the 5 preferred embodiment of my invention, it is of course to be understood that I reserve the right to make such changes in the form, construction and arrangement of parts as will not depart from the spirit of the invention or the scope of the subjoined claims.

I claim:

1. A suspension clamp comprising a U-shaped frame including pivotally connected members carrying clamping plates, 15 a suspension element depending from the bight of the frame, and means for holding the two frame members in clamping relation consisting of a threaded rod pivotally connected with one member and carrying a 20 clamping nut, the other member being formed with a slot extending inwardly from one edge for the reception of said rod.
2. A suspension clamp comprising a U-shaped frame including pivotally connected members carrying clamping plates, a 25 suspension element depending from the frame, means for holding the two frame members in clamping relation consisting of a threaded rod pivotally connected with one 30 member and carrying a clamping nut, the other member being formed with a slot extending inwardly from one edge for the reception of said rod, and a hook slidably engaged upon the threaded rod outwardly 35 of the frame and having its extremity engaging the unslotted edge of said second named member whereby to hold the rod normally against movement along said slot.
3. A suspension clamp comprising a pair 40 of pivotally connected members, suspension means depending from one member, an adjusting screw pivoted on one member, the other member having a notch in one edge thereof receiving said screw, and a hook 45 mounted on the screw and engageable with the opposite edge.
4. A suspension clamp comprising a pair

of pivotally connected members, suspension means carried by one member, an adjustable clamping screw pivotally connected with 50 one member and detachably connected with the other, and hook means carried by the clamping screw engageable with said other member for preventing disconnection.

5. A device of the character described 55 comprising a clamp including a substantially L-shaped section, an upright section hingedly mounted on the end of the horizontal portion of the L-shaped section, the upper ends of both sections being formed 60 with lateral extensions directed toward each other and terminating in enlarged heads, a suspension member depending from the center of the horizontal portion of the L-shaped section, the L-shaped section having 65 one side edge of its upright portion formed with a slot, ears on the inner face of the second named section, a screw member pivoted at one end between said ears and having its other end carrying a clamping 70 nut, said screw being normally received within said slot and a hook member apertured for the passage of said screw and engageable with the unslotted edge of the L-shaped section for holding the screw against 75 swinging movement.

6. A device of the character described comprising a pair of pivotally connected members, suspension means depending from one member, clamping plates carried by 80 both members, a screw pivotally connected with one member for movement in a horizontal plane, the other member having a horizontally extending notch receiving said screw, an adjusting nut on the screw, and a 85 retaining member rotatably engaged upon the screw and adapted to engage against the unnotched edge of the second named member for maintaining the screw in the notch.

In testimony whereof I hereto affix my signature.

IVAN R. TOMES.
